FIRE EXTINGUISHING SYSTEM

Ernest A. Lowe, Fanwood, N. J., and John R. Hamilton, Youngstown, Ohio, assignors, by mesne assignments, of one-half to Ernest A. Lowe, Fanwood, and one-half to Stephen T. Van Houten, Allendale, N. J.

Continuation of application Serial No. 461,945, June 18, 1930. This application September 30, 1936, Serial No. 103,262

6 Claims. (Cl. 169—17)

This invention relates to fire extinguishing apparatus or systems in which overhead and preferably underneath, or floor sprinklers, are employed owing to the character of the hazard as, for instance, in the case of hangars adapted for the storage of aeroplanes or aircraft or other buildings or enclosures in which highly inflammable material is housed.

In all hangar installations ceiling heights are necessarily large and the overhead sprinkler heads or outlets are necessarily located at a great distance from the floor, in order not to interfere with the storage space of the planes, or aircraft.

In aeroplane hangars, a fire is radically different from an ordinary fire in that it acts with such rapidity it has practically been impossible to combat it prior to the advent of the present invention. It is devastating to the extreme in its effects for the reason that a hangar houses a large amount of highly inflammable materials such as high test gasoline, greases and oils as well as highly combustible wing and body fabrics and delicate wood structural members, which make ready tinder. It also acts with great rapidity because of the broad expanse of unobstructed space in the hangar through which a fire sweeps in a minimum of time. The fire may ignite, flash and sweep through the entire hangar all within a few minutes. It is destructive to the highest degree and may, unless promptly curbed, completely destroy the hangar itself as well as the aeroplanes therein which may easily result in a loss of several hundred thousand dollars, especially if the hangar is used as a storage space only in which the aeroplanes are compactly and closely nested together. Seconds, not minutes, measure success in combating aeroplane hangar fires. The heat generated by such fires is intense and explosions frequently characterize them. The intense heat not only destroys the combustible materials in the hangar but warps and wrecks the steel framework of the hangar and the metal portions of the planes themselves.

The present invention has for its general object the provision of improved means whereby a fire may be quickly detected and the application of a fire extinguishing agent, by downwardly and preferably upwardly directed streams of a fire extinguishing medium, such as water, may be quickly brought about, and consists in the improved combination of apparatus and devices organized as hereinafter described to effectually protect the stored contents of an airplane hangar or other closure against destruction by fire through the direct application of the fire ex-

tinguishing medium delivered through suitable outlets directed downwardly and preferably upwardly over the whole storage area to embrace any or all of the airplanes or aircraft that may be for the time being stored on the floor thereof. 5

In the dry-pipe hangar fire extinguishing systems heretofore proposed and employing overhead and underneath or floor sprinklers, the equipment involves the use of overhead fuse controlled sprinkler heads connected to the water distributing piping and normally held closed by their fuses. The melting of said fuses and the opening of the overhead sprinkler head or heads to allow the escape of air under compression in the distributing system, is depended upon to 10 cause opening of the main valve and flow of the fire extinguishing medium through both the overhead and underneath floor sprinklers. Such fuse controlled sprinkler heads must, however, be located high up in the ceiling or roof so as not to 15 interfere with the stored contents of the hanger, in which position any heat collector or heat responsive device designed to control the application of fire extinguishing medium is subjected to 20 heating by the sun through the ceiling or roof 25 to a high degree of temperature. As the control depends upon the melting of the fuse moreover the action under the effect of heat rising from the floor of the hangar and sufficient in amount to melt the fuse, is necessarily slow. 30

In addition to the above, the previous systems using fuse controlled sprinkler heads are obviously at a further disadvantage since at the time of a fire the hangar is apt to be cold as from doors being opened and when a fire occurs the 35 sprinkler head must absorb sufficient heat to bring it to the operating point. Should the attempt be made to control the action of the apparatus by a more sensitive fixed temperature thermostat than the fuse a liability results to 40 the premature operation of the same, due to the fact that a high temperature is liable to collect and accumulate from the heat of the sun and to thereby bring about a premature operation thereof. This transmission of heat from the air to 45 the sprinkler head entails considerable time which is a vital factor in properly controlling and extinguishing fires in this type of building.

As a matter of fact it is found in practice that in the previous systems just referred to the operation of the fuse controlled sprinkler head which brings the main valve into action is too slow in discharging water to the fire from the floor and other sprinklers to be of effective fire fighting value, this delay being, primarily, due to the 50 55

- lapse of time necessary in order that the fuse which keeps the sprinkler head normally closed may be raised to a sufficient temperature to cause it to melt. Further delay ensues, owing to the fact that time is required in order that after the sprinkler head opens the air may escape from the distributing piping system sufficiently to lower the pressure down to the critical pressure at which the main dry valve may trip, or be allowed to open. In practice an average maximum normal pressure of air in the dry pipe of about 45 pounds is usual and a drop of that pressure on the opening of the sprinkler head down to tripping pressure of 17 pounds is relied upon to effect the opening of the main valve. The period of time delay after the main valve trips is further enlarged, for the reason that the air remaining in the system after the dropping to the critical tripping pressure must escape before the water can discharge freely. As fires in hangars are extremely rapid and are of what is called flash character this delay detracts greatly from the efficiency of the system. Furthermore, dependence being placed upon the sprinkler heads in the ceiling to fuse and open the dry piping for the flow of the water or other medium to the overhead and floor outlets there is a further element of delay owing to the extreme ceiling heights necessary in hangars.

The main object of the present invention is to overcome the above and other defects and disadvantages in the aforesaid hangar fire extinguishing systems employing overhead and floor sprinklers.

In the improved system forming the subject of the present application the distributing piping does not contain air under pressure that would delay or interfere with the arrival of the fire extinguishing medium, such as water, to and through the downwardly directed ceiling sprinklers and to and through the upwardly directed floor sprinklers. The sprinklers employed in the ceiling as well as the floor sprinklers are of the normally open type, so that the flow of water or other extinguishing medium will not be delayed by the presence of air banking up in the distributing piping. The opening of the main valve in the present invention, instead of being dependent upon the drop in pressure of the air in the distributing system, is placed upon independent thermal devices placed above the space containing the inflammable storage material and preferably in proximity to the normally open sprinkler heads.

The aforesaid thermal devices are arranged to cover or embrace the whole area of the storage space for the airplanes so that when a fire takes place, either in the airplane itself, or in accumulated oil or other inflammable material on the floor at any point, one or more of said thermal devices will be immediately affected by the rising current of heated air from the fire. The tripping of the main valve is made dependent, not upon the relief of pressure in the main distributing piping, but upon an increase of air pressure in a supplemental piping connected with the thermal or heat collecting devices arranged in the manner described and located in the roof or ceiling of the hangar so as to be well out of the way of the stored aeroplanes or other aircraft and by reason of their construction quickly sensitive or responsive to the heat of the ascending heated air currents rising from the point of origin of the fire. This increased pressure is made effective either by a mechanical or a water trip as will be hereinafter more particularly described. The thermal devices embody preferably sealed

air bulbs or containers of large volume as compared with the diameter of piping through which the pressure of the container is communicated to the controlling devices and are preferably of the rate of rise type. In order that these devices 5 may act upon the rate of rise principle they, or the piping conveying the increased air pressure to the main valve, are provided with suitable restricted air vents which permit escape of the air therefrom when the increased temperature and 10 pressure takes place at a normal rate less than a predetermined rate at which the device should be effective in opening the main valve.

By the means just described, normal changes of atmospheric temperature in the building or 15 storage space, such as would result from the heat of the sun directly falling upon the roof of hangars, and collected and accumulated in the roof through a degree which if continued would result in a production of a temperature of fixed amount 20 or degree sufficient to bring about the operation of the usual heat collector, will not cause the main valve to open but if fire occurs and the temperature rises quickly, or at a rate indicating a condition of danger, said pressure will not be 25 compensated or allowed to escape through the vent sufficiently rapidly to avoid operation of the trip device for the main valve. The thermal device thus constructed is of extreme sensitivity and rapidity of action and is not affected or 30 lessened in efficiency by the extra ceiling heights necessary in installations such as herein referred to and may be depended upon to catch a small fire incapable of operating upon a fuse controlled system such as heretofore employed in connection 35 with hangars.

The general characteristics of the improved system having been described the invention as carried out in one of the particular forms in which it may be used will be now described in connection with the accompanying drawings wherein:

Fig. 1 is a general elevation and partial section of the system as applied to a hangar.

Fig. 2 is a detail view showing a preferred form of water trip adapted for use in connection with the main water valve, or valve admitting the fire extinguishing medium to the distributing pipe.

Fig. 3 shows a form of mechanical trip that may be used as a substitute for the water trip.

The distributing piping leading to the sprinkler heads in the ceiling and floor of the hangar is indicated by the numeral 1. Normally open sprinkler heads in or near the ceiling and adapted to discharge the fire extinguishing medium downwardly upon the contents of the hangar when it flows to said sprinkler heads through the piping 1, are indicated at 2, while 2' indicates normally open sprinkler heads adapted to direct streams of fire extinguishing medium upwardly from the floor when the normally closed main valve 3 opens connection from the source of supply 4 of fire extinguishing medium to the piping 1. Said normally open sprinkler heads 2' may be attached to piping 1 embedded in the floor of the building or hangar and said sprinkler heads 2' may be countersunk, if desired, in depressions in the floor surface to avoid injury to the same.

The normally open sprinklers 2 are conveniently placed at or attached to the top of risers 70 5 extending upwardly from the horizontal distributing pipe 1, or may be otherwise connected to the main valve 3, or the piping leading therefrom so as to be located preferably near the roof or ceiling 6. Located also in the ceiling are sealed

air bulbs 7 preferably, of metal and connected through air piping 8 with the main valve 3. These air containers, or bulbs 7, are as usual of metal, adapted to absorb heat quickly, and to heat the air contents of said containers 7 thereby building up pressure which is communicated through the pipe 8 to the main valve 3 to be there rendered effective through its increased pressure in acting upon a suitable trip device for said main valve 3 whereby said valve, normally held closed by any suitable means, may be caused to open. Said trip may be a water trip or a mechanical trip or one of any other desired character. The compensating vent hereinbefore mentioned is here shown at 9 as applied to the piping 8. One of the aeroplanes to be housed or stored in the hangar is indicated at 10.

In Fig. 2 we show a suitable type of water trip for the main valve that may be employed in carrying out our invention. The parts of this water trip and the controlling devices therefor as shown in this figure may be located entirely within the housing of the valve 3, or parts thereof may be located outside of said housing. In this figure, 25 11 indicates a water valve normally resting on its seat and normally cutting off the passage of the fire extinguishing medium from the pipe 4 to the pipe 12 from which the piping 1 branches. Valve 11 is normally held on its seat against the head of the fire extinguishing medium by means of a supplemental disk or clapper 13 which is acted on by by-pass pressure of the water or other medium in a chamber 13' and passing to said chamber from pipe 4 through a branch pipe 35 14 of restricted capacity and acting on the rear face of the valve clapper or disk 13 to hold the valve 11 closed.

A valve 15 normally prevents escape of the by-pass pressure water through a vent pipe 16 but when said valve 15 is opened the pressure acting on the disk 13 is relieved and the pressure of the medium tending to open the valve 11 is permitted to become effective to open said valve 11. Said medium thereupon flows immediately to the pipe 12 and the distributing pipes 1 and through the same freely and without obstruction from air under pressure and is discharged immediately downwardly through the upper normally open sprinklers 2 and upwardly through the normally open floor sprinkler 2'. The discharged streams of water are thus delivered directly upon the fire at its place of origin to extinguish any incipient fire that may arise at any place over the storage floor space in the hangar or in the stored contents such as the aeroplane 10.

The relief valve 15 is normally held closed by a suitable spring action reinforced by the internal pressure of the by-pass chamber 13' but is opened whenever pressure of sufficient amount in the air piping 8 is developed in the air containers 7 to operate upon or influence a diaphragm 17 which forms a wall of a closed chamber 17' in which the pipe 8 terminates. Said diaphragm acts, when operated, upon a detent lever 18 which normally holds a weight 19 raised but upon release of the weight by the air pressure in 8, said weight falls to the position shown in dotted lines and strikes the upper end of the stem of valve 15 thus depressing the same forcibly and opening the communication between the chamber 13' and escape vent 16. The main valve 11 thereupon opens and the fire extinguishing medium flows as before described.

In the above described operation the action of 75 the diaphragm operated detent 18 is not inter-

fered with at any time by the pressure of the extinguishing medium which would otherwise tend to prevent disengagement of the detent member. Said detent may be therefore disengaged readily by the action of the air pressure diaphragm 17 and its associated heat absorbing air containers 7. Light pressure, therefore, on the diaphragm may be readily made effective by the simple release of the weight which in falling applies proper force to act upon the valve restraining means and free the valve from the action of the latter. The stem of the valve 15 may be sealed by attachment thereof to a collapsible bellows arrangement 20 surrounding the stem and attached to the upper end of the stem 15 as shown. In addition an alarm bell 21 may be caused to sound through the closure of an electric circuit effected by an arm 22 of the weighted lever, said arm impinging upon a member of the circuit closer when the weight is released. 20

In the operation of the system as thus far described the valve controlling the fire extinguishing medium is normally in closed position as shown in Fig. 2 and the sprinkler heads 2 and 2' are both open while air in the piping 1 instead of being under pressure confined therein by normally closed fuse controlled sprinklers as in the prior instance above referred to, is at normal atmospheric pressure. The increased temperature attendant upon fire conditions in the storage space of the hangar quickly affects the air containers located in the ceiling or roof and well above the storage space for the aircraft and there results an increase of pressure therein at such rate and of such amount as to cause the diaphragm 17 to release the weight, thereby relieving by-pass pressure of the water trip valve and admitting the fire extinguishing medium to the piping 1. The extinguishing medium is immediately discharged in upwardly directed streams from the normally open floor sprinklers 2' and downwardly directed streams from the normally open sprinklers 2. There thus results a quick and effective application of fire extinguishing medium without waiting for an accumulation of temperature sufficient to operate slowly acting fuses of the previous system located in the sprinkler heads and without delay from the presence of air normally under pressure in the mains 1 and trapped therein by the normally closed sprinkler outlet as in the previous hangar system.

As will be obvious, in the system of thermal control herein described, inasmuch as it is unnecessary to maintain pressure in the sprinkler piping and inasmuch as all the sprinkler heads are always open, instant delivery of the water or other fire extinguishing medium is accomplished when the thermal system acts, and the discharge of water or other medium from below and above is accomplished quickly enough to hold the fire to its original location thus confining the spread thereof with saving of material and building and eliminating unnecessary water damage. Moreover, the increased sensitiveness and quick action of the rate of rise system is not lessened appreciably by the extreme ceiling height since the heat rises quickly to the roof or ceiling and the thermal device may be depended upon to quench a small fire that would be incapable of operating the fuses of the previous hangar systems hereinbefore referred to. 70

Surface gasoline fires as well known are swift in action and aeroplane structures are peculiarly inflammable and quickly burning but by actual

tests the improved system herein described has proved more effective than any previous system in operating the main valve of the fire extinguishing medium and extinguishing fires in hangars with minimum loss.

Instead of the water trip valve operated in the manner described to admit fire extinguishing medium to the distributing piping and the normally open sprinklers, a mechanical trip valve of the

- 10 form illustrated in Fig. 3 might be employed. In this figure the main water valve is a disk valve 23 normally seated on the valve seat 24 and thereby closing the admission of the medium from the pipe 4 to the piping through suitable connection 25. Said disk valve may have a flexible facing 23' engaging the valve seat and as described in our Patent No. 1,869,204, dated July 26, 1932. The valve disk 23 is held to its seat against the pressure of the first extinguishing medium beneath the valve by a catch 26 and is tripped by engagement of the weighted lever 27 released by the detent or catch lever 18 said weighted lever engaging when released with an arm 28 extending from said pivoted catch 26. The release of the weighted lever and the general action is as already described in connection with the use of the water trip valve. As also will be seen in this case, the control of the tripping action from the pressure actuated diaphragm will not be interfered with by any pressure of the extinguishing medium acting upon the restraining means, to wit: the means 26 for holding the main valve normally closed.

In some cases, our invention, as is obvious, may be applied to structures other than airplane hangars. It will be found exceedingly efficacious, for instance, for installation in Celluloid film plants in which the film is drawn through a tunnel or elongated box-like structure for treating or drying purposes. In these and similar installations the floor sprinklers would be superseded by sprinklers positioned or located on the side walls of the tunnel to discharge streams of water laterally and inwardly instead of upwardly as in the preferred form of the invention, it being understood that the overhead sprinklers also would be employed.

It will be understood also that in the interests of economy, in some cases the floor sprinklers may be entirely eliminated and the apparatus will function effectively nevertheless but not as effectively as if they had been included.

This application is a continuation of our application filed June 18, 1930, Serial No. 461,945.

The invention claimed is:

1. A fire extinguishing apparatus for a hangar comprising overhead normally open sprinklers adapted to direct the fire extinguishing medium downwardly, normally open floor sprinklers adapted to direct the fire extinguishing medium upwardly, said sprinklers being disposed to cover or shroud the whole floor storage area of the hangar, a main valve normally closed and shutting off the passage of fire extinguishing medium to said sprinklers, restraining means normally holding said main valve closed against pressure of the extinguishing medium, trip devices for freeing the restraining means to permit the main valve to open and means for controlling said trip devices comprising air piping connected to air containers located and distributed in the roof of the hangar above the storage space and exposed to the directly ascending heated air currents from the fire at any part of the hangar floor space 75 occupied by an airplane or aircraft and a pressure

responsive diaphragm responsive to increase of pressure in said piping due to increase of temperature at a relatively rapid rate in any portion of the storage area and adapted to control the operation of the trip devices.

2. A hangar installation for controlling and extinguishing fires in hangars consisting of the combination with distributing piping containing air at atmospheric pressure and having overhead normally open sprinklers and normally open upwardly directed floor sprinklers as described and arranged to apply the fire extinguishing medium over the whole floor storage space where a fire may arise directly, a main valve controlling the admission of the fire extinguishing medium to said piping and provided with restraining means for holding the same in closed or inoperative position, rate of rise thermal devices located in the roof or ceiling of the hangar and trip devices operating on said restraining means to free said main valve, said trip devices being controlled by the air pressure generated through heating of said rate of rise device.

3. A hangar installation for controlling and extinguishing fires in hangars consisting of the combination of normally open sprinklers adapted to direct a fire extinguishing medium downwardly and located and disposed over and shrouding the whole floor storage space, normally open floor sprinklers adapted to direct the fire extinguishing medium directly upwardly, piping with which both said sets of sprinklers are in direct communication to permit the free escape of the air when subjected to the compressing effect of the fire extinguishing medium admitted to the sprinklers, a main valve controlling the admission of fire extinguishing medium to said piping, air containers located and distributed in the roof of the hangar above the storage space and embracing or shrouding the whole storage area for the airplanes, air piping connected therewith, a valve, means for holding said valve normally closed and trip devices therefor controlled in their action by abnormal pressure developed in said air piping by abnormal heating of the air containers.

4. In a fire extinguishing apparatus for hangars and in combination, distributing piping containing air at atmospheric pressure and provided with overhead sprinklers and floor sprinklers having normally open outlets, of a main valve controlling the admission of fire extinguishing fluid to said piping and sprinklers and relatively sensitive controlling devices located within and distributed under the roof of said hangar and disposed directly over the floor storage space therein so as to receive the directly ascending air currents from a fire arising at any portion of said floor space, said controlling devices being of the type acting in response to a predetermined rate of rise of temperature instead of on the attainment of a fixed temperature and means extending from said controlling devices to said valve for operating the latter.

5. In a fire extinguishing apparatus for protecting storage areas and in combination, distributing piping for conducting fire extinguishing fluid, normally open overhead sprinklers and normally open upwardly directed floor sprinklers 70 connected with said piping all arranged to apply the fire extinguishing medium to a fire originating at any point on the floor storage space, valve mechanism for controlling the admission of fire extinguishing fluid to said piping and sprinklers

and relatively sensitive means located within and distributed through the space in the roof of the storage area and disposed over the storage portion of the area so as to be exposed to the 5 directly ascending heated air currents arising from a fire at any portion of said area and consisting of rate of rise heat responsive devices for releasing said valve mechanism on the occurrence of a rise in temperature therein at a 10 greater than a predetermined rate.

6. In a fire extinguishing apparatus for hangars or like buildings, distributing pipes containing air at atmospheric pressure and provided with downwardly discharging overhead 15 sprinklers having normally open outlets and upwardly discharging sprinklers having normally open outlets and located respectively at spaced points throughout the areas of the roof zone and storage floor zones of the building, valve mecha-

nism controlling the admission of fire extinguishing fluid to said pipes, and thermally responsive means embodying a system of relatively sensitive controlling devices located at spaced points within the roof zone of said building and directly 5 over the floor zones therein so as to be influenced by directly ascending air currents arising from a fire occurring at spaced points intermediate said floor zones and controlling devices, said controlling devices being of the type acting in response 10 to a predetermined rate of rise of temperature instead of on the attainment of a fixed temperature, and means extending from said controlling devices to said valve mechanism so as to be affected by the action of any one of them for operating the latter.
